RACK OR SIMILAR ARTICLE

Samuel Schoor, Newark, N. J., assignor, by mesne assignments, to Copper Clad Products, Inc., Newark, N. J., a corporation of New Jersey

Application April 27, 1949, Serial No. 2,308

Term of patent 14 years

(Cl. D33—3)

To all whom it may concern:

Be it known that I, Samuel Schoor, a citizen of the United States, residing in the city of Newark, in the county of Essex and the State of New Jersey, have invented a new, original, and ornamental Design for a Rack or Similar Article, of which the following is a specification, reference being had to the accompanying drawing forming a part thereof.

Figure 1 is a view in perspective of my rack, showing my new design;

Figure 2 is a side elevation thereof;

Figure 3 is a top plan view thereof; and

Figure 4 is a detail view of one of the hook elements shown separately for purposes of better illustration.

A characteristic feature of the design resides in the angular disposition of the vertical portion and extreme ends of the strap, and also the twisted portion of the strap.

I claim:

The ornamental design for a rack or similar article, as shown and described.

SAMUEL SCHOOR.
